US0D1021767S

(12) **United States Design Patent** (10) **Patent No.:** **US D1,021,767 S**
(45) **Date of Patent:** **** Apr. 9, 2024**

(54) **BATTERY**

(71) Applicant: **LG Energy Solution, Ltd.**, Seoul (KR)

(72) Inventors: **Hyun Beom Kim**, Daejeon (KR); **Jeong Min Ha**, Daejeon (KR); **Gi Man Kim**, Daejeon (KR); **Dae Hong Kim**, Daejeon (KR); **Sin Woong Kim**, Daejeon (KR); **Se Young Oh**, Daejeon (KR); **Geun Hee Kim**, Daejeon (KR); **Hyung Ho Kwon**, Daejeon (KR)

(73) Assignee: **LG Energy Solution, Ltd.**, Seoul (KR)

(**) Term: **15 Years**

(21) Appl. No.: **29/814,802**

(22) Filed: **Nov. 9, 2021**

(30) **Foreign Application Priority Data**

Jun. 3, 2021 (KR) 30-2021-0026551

(51) **LOC (14) Cl.** **13-02**

(52) **U.S. Cl.**

USPC **D13/103**

(57) **CLAIM**

The ornamental design for a battery, as shown and described.

DESCRIPTION

FIG. 1 is a front perspective view of a battery according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of area 8 circumscribed within FIG. 1;

FIG. 9 is an enlarged detail view of area 9 circumscribed within FIG. 4; and,

FIG. 10 is an enlarged detail view of area 10 circumscribed within FIG. 4.

The broken lines in the drawings depict portions of the battery that form no part of the claimed design.

1 Claim, 7 Drawing Sheets
